US0D1023035S

(12) **United States Design Patent** (10) Patent No.: **US D1,023,035 S**
(45) Date of Patent: ** Apr. 16, 2024

(54) **DISPLAY SCREEN OR PORTION THEREOF WITH GRAPHICAL USER INTERFACE**

(71) Applicant: **K-Bio HealthCare, Inc.**, Seoul (KR)

(72) Inventor: **Sang Ho Lee**, Seoul (KR)

(73) Assignee: **K-Bio HealthCare, Inc.**, Seoul (KR)

(**) Term: **15 Years**

(21) Appl. No.: **29/839,915**

(22) Filed: **May 25, 2022**

(51) LOC (14) Cl. **14-04**

(52) U.S. Cl.

USPC **D14/485**

CLAIM

The ornamental design for a display screen or portion thereof with graphical user interface, as shown and described.

DESCRIPTION

The FIGURE is a front view of a display screen or portion thereof with a graphical user interface, showing our new design thereof.

The outer broken lines in the FIGURE show a display screen or portion thereof, and form no part of the claimed design. The other broken lines in the FIGURE show portions of the graphical user interface, and form no part of the claimed design.

1 Claim, 1 Drawing Sheet
